UNITED STATES PATENT OFFICE.

ALLAN J. COLEMAN, OF PITTSBURGH, PENNSYLVANIA.

FORCE AND SUCTION PUMP.

1,040,276.

Specification of Letters Patent.

Patented Oct. 8, 1912.

Application filed June 22, 1911. Serial No. 634,839.

To all whom it may concern:

Be it known that I, ALLAN J. COLEMAN, a resident of Pittsburgh, in the county of Allegheny and State of Pennsylvania, have 5 invented a new and useful Improvement in Force and Suction Pumps, of which the following is a full, clear, and exact description, reference being had to the accompanying drawings, forming part of this specification, 10 in which—

Figure 1 is a view partly in side elevation and partly in vertical section of a pump embodying my invention; Fig. 2 is a vertical section of the elastic cup; Fig. 3 is a vertical 15 section showing the cup attached to the pump cylinder in inverted position; Fig. 4 is a bottom plan view of a portion of the cup; and Fig. 5 is a detail sectional view showing a modification.

20 My invention has relation to force and suction pumps, and more particularly to pumps of the character used by plumbers or others for forcing or drawing obstructions from plumbing fixtures.

25 My invention relates specifically to the elastic cup members which are employed with pumps of this character, and is designed to provide a cup having means for increasing its adhesion and also having 30 means of improved character for its attachment to the pump cylinder.

Referring to the accompanying drawings, the numeral 2 designates the pump cylinder, 3 the pump piston, 4 the piston rod, and 5 the operating handle.

6 designates my improved elastic cup which is of the usual bell form, but which, instead of having the usual flat surface or single circular groove in its lower or suction edge is, in accordance with my invention, provided with a plurality of adjacent concentric grooves 7, which may be of the same or different depths. I have found that by employing a plurality of 40 these concentric grooves, the suctional adhesion of the cup is very greatly increased, thereby increasing largely the suction power 45 of the pump. In accordance with my invention, I also mold and vulcanize into the small or neck portion of the cup a metal thimble bushing 8. In the form shown in Figs. 1, 2 and 3, this bushing or thimble is formed with an internal screw thread to

receive the internal thread of a nipple projection 9, at the lower end of the cylinder. 55

In the modification shown in Fig. 5, the thimble 8^a and nipple 9^a instead of having a screw-threaded engagement, have a tapered engagement and are also preferably united by bayonet lock or joint 10. By 60 molding or vulcanizing the bushing or thimble within the neck of the cup, I provide secure and permanent means for attaching the cup to the pump.

The cup may, as shown in Fig. 3, be used 65 in inverted position for application to relatively small orifices, the neck end of the cup either being applied to the surface surrounding the orifice or extending into the orifice according to the size of the latter. 70 The shape of the neck portion is such as to adapt it to orifices of varying diameters. The neck end of the cup is preferably provided with a plurality of concentric suction grooves 11, similar to the grooves 7, 75 before described.

Instead of attaching the cup to a pump cylinder of the type shown, I may attach it to a hollow tube or cylinder whose opposite end is plugged or otherwise sealed, and 80 thereby very greatly increase the efficiency of the adhesive and sucking action of the cup.

The advantages of my invention result 85 from the provision of the plurality of suction grooves, above described, whereby the adhesion of the cup to the surface to which it is applied is very largely increased, and also from the provision of the novel and highly effective means for attaching the cup 90 to the pump cylinder.

I claim:

1. An elastic suction cup for pumps, having its lower edge formed with a plurality of concentric suction grooves of varying 95 depth, substantially as described.
2. An elastic suction cup for pumps, having the edge of its neck or smaller end formed with a plurality of concentric suction grooves, substantially as described. 100
3. An elastic suction cup for pumps, said cup being reversible and having both its upper and lower edges provided with a plurality of concentric suction grooves, substantially as described. 105
4. A reversible elastic suction cup for

pumps, having both its upper and lower edges provided with three suction grooves, the central groove being of greater depth than the grooves adjacent thereto, substantially as described.

5. An elastic suction cup for pumps, having a metallic thimble or bushing embedded within the neck portion thereof, and having both its upper and lower faces provided

with a plurality of concentric grooves of varying depths, substantially as described.

In testimony whereof, I have hereunto set my hand.

ALLAN J. COLEMAN.
